(57) **CLAIM**

The ornamental design for a hair remover, as shown and described.

DESCRIPTION

FIG. 1 is a perspective view of a hair remover showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the hair remover with the cap on;

FIG. 10 is an enlarged view of a portion of the hair remover, shown within the area designated as 10 in FIG. 1; and,

FIG. 11 is an enlarged view of a portion of the hair remover, shown within the area designated as 11 in FIG. 2.

The dash-dash broken lines in the drawings are for the purpose of illustrating portions of the hair remover that form no part of the claimed design. The dot-dash broken lines encircling portions of the hair remover in FIGS. 1 and 2 and illustrated in the enlarged views in FIGS. 10 and 11 form no part of the claimed design.
